FIRE ALARM

Tadeusz Ślusarz, Warsaw, Poland

Application January 14, 1937, Serial No. 120,463
In Germany November 19, 1936

7 Claims. (Cl. 200—136)

Fires frequently assume great dimensions because the fire is noticed too late. The fire is often only noticed after it has made its way to the outside of the building. This is in particular the case with factories and warehouses, museums and similar buildings in which work ceases during the night.

Fire alarm devices are already known which are caused to operate by means of the fusing or expansion of an indicating substance taking place with a sudden rise of temperature. These devices are, however, objectionable since they frequently give an indication only when in consequence of the fire the temperature has risen by several degrees.

The present invention relates to a device which indicates the outbreak of a fire even if the temperature of the room in which the device is situated has risen under the influence of the fire by only a few degrees, and this independently of the temperature prevailing in the said room before the fire started.

According to the present invention any desired alarm device is actuated by means of a small freely suspended container which in consequence of the alteration in the density of the surrounding air, caused by the fire, sinks and thereby switches in or out the alarm device.

The weight of the air, as is known, is reduced in inverse ratio to the temperature of the air and the air in a confined space, e. g., in a room, will be heated under the direct influence of the flames more quickly than under the effect of climatic changes or central or stove heating. This fact is utilized in the construction of the device according to the present invention, the walls of the container being given such a degree of heat conductivity that the device only responds to fire but not to a gradual rise of temperature.

In the accompanying drawing is shown a construction of the device according to the present invention, by way of example:

Figure 1 is an elevation of the device; Figure 2 is a vertical section through the device according to Figure 1; and Figure 3 is a horizontal section through the device on the line A—B of Figure 2.

The device according to the present invention comprises a casing 1, which contains three chambers a, b, c. In the central chamber b is mounted the balance frame 2 with the balance beam 3. On one end of the balance beam is suspended in the chamber c a small container 4 and at the other end of the balance beam there is suspended a counterweight 5. The device is provided with

one single container 4, while the counterweight 5 consists of a piece of sheet metal having surfaces equal in area to the outer surfaces of the container 4, so that the weight of the dust settling on the container 4 will be equal to the weight of the dust settling on the counterweight 5. The counterweight 5 is preferably corrugated and has the form of an open cylinder having no bottom. One pole V of the source of current is connected to the casing 1, whilst the other pole V' is insulated from it and is introduced into the interior of the casing. The balance beam consequently on the increase of the weight of the container touches the pole V', closes the current circuit and thus switches on the alarm device (not shown). In the wall of the chamber b there is inserted in the current circuit a checking incandescent lamp 6.

The balance beam 3 is in its usual position slightly overloaded on the side of the counterweight in such manner that it rests by means of the spring 8 on the pin 7. This spring prevents any bouncing of the balance beam from the supports in the case of the apparatus being shaken, so that no false alarm is caused thereby.

The casing 1 is provided with lugs 9 intended to fasten the device on the wall, and also with a plumb bob 10.

In order to ensure the operativeness of the device, its essential parts, namely the container, the balance beam and the counterweight, must be most carefully protected from injury which might be caused by dust, insects, draught and the like. For this reason, the device is provided with an envelope 11 which is situated within the casing 1 and around the container 4 and which permits the inflow of the heat to the interior of the chamber c but at the same time to a large extent protects these constituents of the device from external influences. The envelope 11 is either made from a very dense fabric or from a very thin metal plate of great heat conductivity. The envelope 11 encloses the chamber c in which the container 4 is situated. The openings 12 of the casing 1 are covered by caps 12'. As the casing 1 cannot be closed air-tightly, it does not protect the small container 4 completely from the penetration of small particles of dust, so that it would be possible for the container at the expiration of a certain time and under the influence of this load, to fall and effect an unnecessary alarm. To prevent this, the counterweight is made of the same material as the container 4 and has a similar surface to the container, so that the

amount of the dust settling on both sides of the balance beam must always be the same.

Since, under the influence of the varying barometrical pressure, the density of the air and with it also the weight of the air in the room undergo variations whilst the weight of the air enclosed in the container 4 always remains the same, this might lead to an undesired deflection of the balance in one direction or the other, and 10 thus to an unnecessary alarm. To prevent this, the container 4 has an opening 13 provided with a cover 13' which permits outside air to penetrate gradually into the interior of the container 4, so that in case of a change in atmospheric 15 pressure around the container 4 a gradual equalisation of the density of air on the outside and inside of the container 4 can take place. However, the cover 13' prevents dust from reaching the interior of the container 4. The cover 13' may 20 be made of a dense fabric or the like.

The device operates in the following way:

At the outbreak of a fire, there is a sudden rise in the temperature of the air in the room in which the alarm device is situated. The warmed 25 air passes through the openings 12 of the casing 1 through the envelope 11 into the interior of the chamber c which results, in a rapid heating of the air in the chamber c, if the envelope 11 is made of a thin metal plate of good heat 30 conductivity. The decrease thereby caused in the density of the air surrounding the container 4 causes the sinking of this latter, whereby the balance beam 3 comes into contact with the contact piece V' and switches in the alarm device.

35 Since the counterweight 5 is open at the bottom, no separate means to compensate for ambient temperature changes are required for the compartment a. The clearance in the compartment b is not sufficient to have a balancing effect of the 40 ambient air in the compartments a and c.

Having now particularly described and ascertained the nature of my said invention and in what manner the same is to be performed, I declare that what I claim is:

45 1. In a fire alarm having a normally balanced beam, a hollow container filled with air suspended from one end of said beam and having walls which are rapid and excellent conductors of heat, means connected with said beam for balancing the same, and means connected with said beam for closing an electrical circuit when said beam is thrown out of balance due to a change in the buoyancy of said container resulting from an abnormally quick rise in temperature of the air surrounding said container.

50 2. In a fire alarm having a normally balanced beam, a hollow container filled with air suspended from one end of said beam and having walls which are rapid and excellent conductors of heat, means connected with said beam for balancing the same, means connected with said beam for closing an electrical circuit when said beam is thrown out of balance due to a change in the buoyancy of said container resulting from an abnormally quick rise in temperature of the air surrounding said container, a casing surrounding said container and having openings formed therein, and caps covering said openings.

55 3. In a fire alarm having a normally balanced beam, a hollow container suspended from one end of said beam and having walls which are rapid and excellent conductors of heat, means connected with said beam for balancing the same,

means connected with said beam for closing an electrical circuit when said beam is thrown out of balance due to a change in the buoyancy of said container resulting from an abnormally quick rise in temperature of the air surrounding said container. 10

4. In a fire alarm having a normally balanced beam, a hollow container suspended from one end of said beam and having walls which are rapid and excellent conductors of heat, means connected with said beam for balancing the same, 15 means connected with said beam for closing an electrical circuit when said beam is thrown out of balance due to a change in the buoyancy of said container resulting from an abnormally quick rise in temperature of the air surrounding said 20 container, a casing surrounding said container and having openings formed therein, and an envelope consisting of a thin metallic plate of high heat conductivity, said envelope being situated within said casing and surrounding said container. 25

5. In a fire alarm having a normally balanced beam, a hollow container suspended from one end of said beam and having walls which are rapid and excellent conductors of heat, a corrugated counterweight suspended from the other end of said beam to balance the same, the area of the surfaces of said counterweight being equal to that of the surfaces of said container, and means connected with said beam for closing an electrical circuit when said beam is thrown out of balance due to a change in the buoyancy of said 30 container resulting from an abnormally quick rise in temperature of the air surrounding said container. 35

6. In a fire alarm having a normally balanced beam, a hollow container suspended from one end of said beam and having walls which are rapid and excellent conductors of heat, said container having an opening formed therein, means closing said opening and permitting a gradual equalization of air in the interior of said container with the air surrounding said container upon variation of barometric pressure, means connected with said beam for balancing the same, and means connected with said beam for closing an electrical 45 circuit when said beam is thrown out of balance due to a change in the buoyancy of said container resulting from an abnormally quick rise in temperature of the air surrounding said container. 50

7. In a fire alarm having a beam, a hollow container suspended from one end of said beam and having walls which are rapid and excellent conductors of heat, a counterweight suspended from the other end of said beam and being somewhat heavier than said container, whereby said beam is normally somewhat overloaded on the side of said counterweight, a spring carried by said beam, a pin engaged by said spring in the overloaded position of said beam, whereby said beam is resting on said pin in said overloaded position, and means connected with said beam for closing an electrical circuit when said beam is moved out of said overloaded position due to a change in the buoyancy of said container resulting from an abnormally quick rise in temperature of the air surrounding said container. 65 70
